UNITED STATES PATENT OFFICE.

JOSEPH C. ANDERSON, OF CORDOVA, ALABAMA.

HINGE.

No. 823,911.

Specification of Letters Patent.

Patented June 19, 1906.

Application filed June 24, 1905. Serial No. 266,830.

To all whom it may concern:

Be it known that I, JOSEPH C. ANDERSON, a citizen of the United States of America, residing at Cordova, in the county of Walker 5 and State of Alabama, have invented new and useful Improvements in Hinges, of which the following is a specification.

This invention relates to improvements in hinges, and particularly to hinges for screen-doors, one object of the invention being to provide a hinge composed of members adapted to be permanently secured, respectively, to the door-frame and door, the member on the door being adapted to detachably engage 15 the member on the door-frame, whereby the door may be applied for use and removed without the necessity of detaching any screws or other fastenings and by the aid of unskilled labor without marring the door-frame.

Another object of the invention is to provide improved means for holding the members assembled and permitting of their ready detachment and also to provide spring means 25 for positively holding the door in either full open or closed position.

Another object is to provide a hinge of this character which is simple, durable, reliable, and efficient and adapted to be inexpensively 30 manufactured.

The preferred embodiment of the invention is illustrated in the accompanying drawings, in which—

Figure 1 is a front elevation of the complete hinge. Fig. 2 is a rear elevation of the same. Fig. 3 is a central section on the line 33 of Fig. 1. Fig. 4 is a bottom plan view. Fig. 5 is a perspective view of the keeper member of the hinge, and Fig. 6 is a detail 40 cross-section on line 66 of Fig. 2.

The hinge comprises three main parts or members 1, 2, and 3. The part 1 consists of a keeper-plate provided at its outer edge with openings 4 for the passage of screws to 45 permanently secure the same to the hinging-jamb of a door-frame. The outer face of this plate is reduced or cut away from a point adjacent to the openings 4 to its inner edge to form a seat for the reception of the member 2, so that the outer face of the latter will lie 50 flush with the outer edge of the keeper-plate. The inner edge of the keeper-plate is curved or rounded, as shown at 5, to permit the part 3 of the hinge to swing without interference, 55 and in its reduced face said keeper-plate is provided with a longitudinal dovetailed slot

or recess 6, flaring or diminishing in width toward its lower end. The inner edge of the keeper-plate is also formed with openings 4' 60 for the passage of screws to supplement the action of the screws entered through the holes 4 to secure said plate firmly and securely to the door-frame. On the inner edge of the keeper-plate, adjacent to the lower end thereof, is a retaining-lug 7, the 65 function of which will be hereinafter described.

The member 2 of the hinge constitutes an attaching-leaf for connecting the hinge proper to the door-frame. This leaf is adapted to snugly seat against the recessed portion of the face of the keeper-plate 1 and is formed on its inner face with a wedge-shaped dovetailed locking key or rib 8, adapted to engage the dovetailed slot 6, the construction 75 being such that the leaf 2 is adapted to be applied and removed by a longitudinal sliding movement of the same on the keeper-plate. The locking-rib is inserted and removed through the upper end of the slot 6, and the 80 said rib 8 when applied holds the hinge member firmly connected with the keeper-plate.

The member 3 constitutes an attaching-leaf adapted to be fastened to the edge of the door and is provided with openings 9 for the 85 passage of screws for that purpose. This leaf is properly shaped at its inner edge to accommodate a substantially semicircular shield or casing 10, formed on the outer edge 90 of the member 2 and open on its inner side and at its upper end. The casing is provided at its lower end with a bottom wall 11, formed with an open bearing slot or recess 12 to receive a pintle-pin 13, carried by an ear 14, projecting from the lower edge of the 95 member 3. At its upper end the member 2 is provided with a bearing ear or boss 15, overhanging the open upper end of the casing 10 and having a bearing slot or recess 16 to receive a pintle-pin 17, projecting upwardly from an ear 18, carried by the member 3 and projecting between said boss and shield or casing, the member 3 thus being pivotally mounted to swing on the two pintle-pins 13 and 17 and to be detached by adjusting one of the members relatively to the other to move said pins out of said bearing-recesses.

In order to hold the members 2 and 3 connected, I provide a spring-plate 19, arranged 110 within the shield or casing and detachably secured therein by a removable transverse

pin 20. The lower end of this spring-plate bears against a seat 21, formed upon the wall 11 and against the inner end of the pintle 13, thus maintaining a desired frictional pressure 5 on said pintle-pin. The upper end of the spring-plate is bent inward slightly to form a bearing portion which engages a detent-pin 22 depending from the ear 18 into the upper end of the knuckle-casing, said spring and 10 detent-pin thus serving to hold the members 2 and 3 connected. By removing the pin 21 the spring-plate may be detached and the members 2 and 3 disconnected in an obvious manner. The detent-pin 22 is of angular 15 form in cross-section and provides oppositely-disposed flat faces 23 and a bearing edge 24. When the door is fully opened or closed, or, in other words, when the leaf 3 is disposed in alinement with or swung outwardly beyond 20 a right-angular relation to the plate 2, the upper end of the spring bears against one or the other of the flat faces 23 and simply maintains the desired amount of pressure thereon to prevent the door from being jarred out of 25 position. The bearing edge 24 is so disposed as to directly engage the spring when the leaf 3 is at right angles to the leaf 2, in which position the spring will therefore exert a binding action to hold the door so disposed. When 30 the door swings slightly outward beyond this position or is only partly opened, however, a full bearing action between the spring and bearing edge of the detent-pin will not be obtained and said edge will act in the nature of 35 a cam in connection with the spring to thrust the door to a fully open or fully closed position. Provision is thus made for preventing the door from standing slightly ajar and positively closing it, except when it is desired to 40 have it held fully open.

It will be understood in practice that the part 1 is intended to be permanently fastened to the door-frame and the part 3 to the door, so that when it is desired to hang or detach the 45 door it is simply necessary to adjust the door to bring the dovetailed locking-rib into and out of engagement with the keeper-socket 6, thus obviating the necessity of employing skilled help and removing the hinges and 50 marring the door-frame.

In order to prevent casual disconnection of the hinge proper from the keeper-plate when the door is hung, I provide the member 3 with retaining means to coöperate with the retaining-lug 7. To this end I construct 55 the ear 14 so that it will serve also as a lug to engage under the lug 7, thus preventing the door from being accidentally lifted off its hinges. The lug 14 is substantially circular in form and is provided with a cut-away portion 25, adapted to permit the same to clear the lug 7 when the hinge member 3 is fully swung to its open position, whereby the hinge proper may be conveniently attached to and detached from the keeper-plate. 60

Having thus described the invention, what is claimed as new is—

A hinge of the character described comprising a keeper-plate provided with a recessed face forming a seat portion, said seat portion having a longitudinal dovetailed slot, a hinge proper comprising pivotally-connected leaves, one of said leaves having a dovetailed lug to engage the slot in the keeper-plate, the pivotal connections of the 70 leaves comprising detachable engaging portions, a spring associated therewith to hold the same in pivotal engagement, one of the pivotal portions of one of the leaves carrying a detent-pin of angular form in cross-section to provide oppositely-disposed flat faces and a bearing edge to engage and co-operate with the spring, the lug-carrying leaf being shaped to engage the seat of the keeper-plate so that its outer face will lie 75 flush with the unrecessed portion of said plate, and a projection upon the other leaf coöperating with the retaining-lug on the keeper-plate to hold the leaves from disconnection, said projection being provided with a cut-away portion to clear said retaining-lug when the door-carrying leaf is swung to fully open 80 position.

In testimony whereof I affix my signature in presence of two witnesses.

JOSEPH C. ANDERSON.
